PAINT KIT

Kenneth G. Emmons, Detroit, Mich.

Application August 2, 1947, Serial No. 140,672

Term of patent 3½ years

(Cl. D74—17)

To all whom it may concern:

Be it known that I, Kenneth G. Emmons, a citizen of the United States, residing at Detroit, in the county of Wayne and State of Michigan, have invented a new, original, and ornamental Design for a Paint Kit, of which the following is a specification, reference being had to the accompanying drawing, forming part thereof.

Fig. 1 is a top plan view of a paint kit, showing my new design;

Fig. 2 is a side elevational view; and

Fig. 3 is a fragmentary cross sectional view taken along the line 3—3 of Fig. 1.

The essential features of my design reside in the parts shown in full lines.

I claim:

The ornamental design for a paint kit, substantially as shown and described.

KENNETH G. EMMONS.
